ALBERT F. FIFIELD, OF ELIZABETH, NEW JERSEY, ASSIGNOR TO THE SINGER MANUFACTURING COMPANY, A CORPORATION OF NEW JERSEY.

STITCH-FORMING MECHANISM.

1,147,386.

Specification of Letters Patent. Patented July 20, 1915.

Application filed April 1, 1914, Serial No. 828,663.

To all whom it may concern:

Be it known that I, ALBERT F. FIFIELD, a citizen of the United States, residing at Elizabeth, in the county of Union and State of New Jersey, have invented certain new and useful Improvements in Stitch-Forming Mechanisms, of which the following is a specification, reference being had therein to the accompanying drawings.

10 This invention relates more particularly to an improvement in stitch-forming mechanism for producing groups of overseam or tacking stitches in which each loop of the stitching thread is entered by a subsequently formed loop of the same thread; and it has for its primary object to provide means for insuring the enchainment of the stitching-thread loops.

In its preferred form, the improvement is embodied in a sewing machine comprising a laterally jogging work-holder and a rectilinearly reciprocating needle with a rotary looper adapted to seize a thread-loop from the needle and spread the same for passage 25 of the needle in the succeeding stitch-forming operation. With the described type of stitch-forming mechanism, it is essential that the thread-loops shall extend from the fabric at one side of the needle-path and shall be held distended by the looper at the opposite side of the needle-path in order to insure the passage of the needle through the same. A laterally jogging work-clamp so shifts the work relatively to the needle that 35 the lead of the thread-loops is alternately from opposite sides of the needle-path so as to cause the skipping of each alternate stitch.

To insure the proper coöperation of the needle and looper in each stitch-forming cycle, the looper is given in addition to its normal loop-seizing movements also bodily jogging movements in the same direction as those of the work-holder so as to carry the needle-thread loops retained by the looper into engagement with a fixed loop-detaining spur upon the opposite side of the needle-path from the loop-spreading portion of the looper in its loop-seizing stage of movement, thereby insuring the positioning of the needle-thread loops uniformly for successive stitch-forming cycles regardless of the position of the connection of the loops with the work under the action of the work-holder jogging means.

To further insure the effective coöperation of the needle with the looper having the described movements, a needle-guard is provided which not only partakes of the lateral jogging movements of the looper, but has additional reciprocal movements toward and from the looper so as to accommodate itself to the loop-seizing movements of the latter while performing its normal function in preventing the injurious engagement of the needle by the looper-point.

In the accompanying drawings, Figure 1 is a front side elevation of a Singer flat-button sewing machine embodying substantially the constructive features of that represented in the United States patent to J. J. Sullivan No. 777,564, of December 13, 1901, and provided with the present improvements, and Fig. 2 is a bottom view of the same. Fig. 2^a is a top plan view showing the relation of the detent-finger and point of the looper. Fig. 3 is a front end view of the same upon a larger scale with the bracket-arm and parts carried thereby omitted. Figs. 4 and 5 are detail sectional front end views showing the stitch-forming elements and their accessories, and Fig. 6 is a perspective view of the loop-detaining spur and the plate by which it is secured in position. Fig. 7 is an elevation showing the swiveled bearing for the looper and needle-guard shafts and the needle-guard actuating means, and representing the bed-plate in section. Fig. 8 is an elevation showing the jogging means for the looper-shaft and needle-guard shaft.

The machine is constructed with a frame comprising the bed-plate 1 from which rises the hollow standard 2 of the bracket-arm provided with the tubular member 3 terminating in the hollow head 4 in which is journaled the rectilinearly reciprocating needle-bar 5 carrying the needle 6 which operates in the production of stitches with a well known form of chain-stitch looper provided with the point or beak 7 and loop-spreading wing 8.

As represented in the said Patent No. 777,564, the work-holder comprises the jogging bar 9 to the forward end of which is secured the lower work-supporting plate 10 upon which rests a button-clamp comprising the button-gripping element 11 and spring supporting plate 12 both secured to the spring-pressed arm 13 secured upon the block 14 mounted upon the rearward end of

the bar 9. The bar 9 is connected by suitable means intermediate its ends with the slide-plate 15 beneath the bed-plate which has a link connection 16 with one arm 17 of the bell crank fulcrumed at 18 and provided with a slotted arm 19 connected in turn by means of the link element 20 with the lower arm 21 of a rock-lever depending through a suitable aperture in the bed-plate. Said rock-lever 10 carries upon its upper arm the roller-stud 22 entering an actuating cam-groove 23 in the controlling cam 24 suitably connected with the main-shaft 25 of the machine for imparting to the work-clamp jogging movements crosswise of the bed-plate and hence 15 in the plane of rotary movement of the looper-point.

The looper is fixed upon the forward end of the rotary looper-shaft 26 provided at its 20 rearward end with the sprocket-wheel 27 connected by means of the belt 28 with a similar sprocket-wheel 29 of the same size upon the main-shaft 25. Secured upon the bottom of the bed-plate beneath the bracket-arm standard 2 by means of the screws 30 is the bearing plate 31 formed with the upwardly extending boss 32 having a vertical bearing aperture to which is fitted the stud 33 of the swiveled bearing block 34 apertured to afford the rearward bearing of the 25 looper-shaft 26. The bearing block is sustained by means of the screw 35 tapped into the stud 33 and having interposed between its head and the boss 32 the washer 36.

Depending from the bed-plate near its 35 front end is the member 37 formed with the transverse slide-way 38 closed at the bottom by means of the divided plate 39 having its component sections notched in their adjacent edges to form the slot 39' and secured to the member 37 by means of the screws 40. Within the slide-way 38 is the slide-block 41 transversely apertured to afford the forward bearing for the looper-shaft 26. The shaft 45 26 has fixed thereon near the slide-block 41 the eccentric 42 embraced by a strap 43 at one end of the connecting rod 44 whose apertured opposite end embraces the screw-bolt 45 sustained by the depending lug 46 of the plate 47 which is secured to the bottom of the bed-plate by the screws 48. As the eccentric-strap 43 is movably maintained a fixed distance from the stationary stud-bolt 45 by the connecting-rod or radius-bar 44, 55 each rotation of the eccentric 42 with the shaft 26 causes a lateral jogging movement of the latter with its slide-block 41, the swiveled bearing block 34 permitting the free horizontal vibratory movement of the 60 shaft about the stud 33 as a fulcrum.

The component elements of the work-holder are provided each with an aperture of sufficient length to receive the needle in either of the extreme lateral positions of the 65 work-holder, and the throat-plate 49 has a

registering needle-aperture 50 elongated in the direction of lateral movement of the work-holder for a like purpose. Secured upon the bottom of the throat-plate by screws 51 is the shank 52 of a thread-detaining finger 53 partially crossing the needle-aperture 50 of the throat-plate and having a recess 54 near its point upon the side opposite which the looper-point advances in its coöperation with the needle. As represented in Fig. 6, the finger 53 is beveled upwardly upon its lower edge.

The bearing block 34 has a depending portion apertured to afford a bearing for the rearward end of the needle-guard rock-shaft 55 whose opposite end portion is mounted within the bearing sleeve 56 sustained by the web 57 extending from the slide-block 41 through the slot 39' in the sectional plate 39. The rock-shaft 55 has fixed upon its forward end the hub of the substantially crescent-shaped needle-guard 58 having its operative end in practice slightly beveled upon one face to engage the portion of the needle below the eye upon the side upon which the needle-thread loop is seized by the looper-point, the point of the needle-guard being directed oppositely to the looper-point in the loop-seizing stage of the stitch-forming cycle.

Fixed upon the needle-guard rock-shaft adjacent the bearing block 34 is the hub 59 of a cam-follower formed with the angularly disposed arms 60 and 61 of which the former has a rounded end. The shaft 55 100 has secured thereon the collar 62 interposed between which and the lug 63 depending from the bed-plate is the torsional spring 64 having one end secured to said collar and the other to the lug 63, whereby the follower-arm 60 is maintained in constant contact with the segmental cam 65 whose hub 66 is adjustably secured upon the looper-shaft 26. As shown in Fig. 7, the periphery of the cam 65 is concentric with the looper-shaft on one side and is flattened upon the other side, and the arms 60 and 61 of the follower are connected upon the side adjacent the looper-shaft in a curve which is concentric with the higher or concentric portion of the cam 65. When the concentric portion of the cam is presented to the follower, the needle-guard is locked retracted from operative relation with the needle and beyond the range of movement of the looper, 115 as represented in dotted lines in Fig. 4, but as the cam continues its rotation to present its flattened side to the follower, the rounded end of the follower-arm 60 rides down the flattened side of the cam under the 120 action of the spring 64 which advances the needle-guard into operative relation with the needle just before the needle-thread loop is seized by the point of the looper, as shown 130 in Fig. 5.

In the use of the machine as thus described, a button *b* is placed in the button-sustaining member of the work-holder and the material *m* introduced intermediate the same and the work-supporting plate 10 and the machine set in motion. Referring to Figs. 3, 4 and 5, when the clamp is in its right-hand position, the needle descends through the left-hand hole of the button and its loop is seized by the looper and in the continued rotation of the looper is carried first to the left as indicated in dotted lines in Fig. 4, and then to the right where it is distended by the spreading wing 8 of the looper, the upper portion of the loop leading to the left of the needle owing to the shift of the work-holder in the same direction subsequent to the initial rise of the needle above the work, as represented in Fig. 5. In the succeeding rotation of the looper a thread-loop is seized from the needle and passed through that held spread by the looper in a manner well known. In the subsequent shift of the work-clamp or holder from right to left, the normal lead of the thread-loop would be from the right of the needle while the succeeding needle-loop would be carried by the looper away from the previous loop held spread by the looper, and the interlooping of the threads would be prevented. By the provision of the loop detaining finger 53 and the looper-jogging means, the thread-loop leading from the material beneath the right-hand hole of the button, as represented in Fig. 4, is initially carried to the left, as indicated in dotted lines in said figure, sufficiently to be drawn over the tapered and slightly rounded point of the detaining finger or spur 53 and to snap into the recess 54 behind the same whereby the upper portion of the loop is retained while the lower portion is carried to the right and to the opposite side of the needle-path in which position the succeeding needle-thread loop is passed through it under the same conditions as would exist in the position of the work-holder represented in Fig. 5. Upon the release of the distended thread-loop by the spreading wing 8 of the looper, it is drawn up on the recessed side of the thread-detaining finger to the lower face of the work.

In the coöperation of the needle and looper for the stitch-forming action, the needle-guard 58 advances from its retracted position as represented in Fig. 4, to its operative position as represented in full lines in Figs. 4 and 5, preparatory to the loop-seizing action of the looper, and just as the point of the looper passes through the loop of needle-thread presented by the needle the needle-guard recedes at a rate exceeding the speed of the looper-point, so as to reach its retracted position beyond the range of movement of the looper before the latter

crosses the path of movement of the needle-guard, whereby interference between the two is prevented, the needle-guard being positively held in its retracted position by the actuating cam, as before explained. 70

From the foregoing description it will be observed that a characteristic feature of the present improvement is the movement of the loop-taker in such manner that it not only seizes and spreads each needle-thread loop for passage of the succeeding needle-thread loop, but carries such thread-loops laterally into engagement with the loop-detaining spur or finger to compensate for the relative lateral jogging movements between 80 the needle and the work-holder. It is evident that the particular means employed for effecting this action and the form and arrangement of the several thread manipulating parts and their accessories may be modified materially within the scope of the present invention.

Having thus set forth the nature of the invention, what I claim herein is:—

1. In a sewing machine, the combination 90 with a reciprocating needle, work-sustaining means, and means for producing between them relative lateral jogging movements, of a loop-taker for seizing thread-loops from the needle and presenting them 95 for subsequent passage of the needle, a stationary loop-detaining spur disposed intermediate the work-sustaining means and the loop-taker, and means for imparting to the loop-taker operative movements for seizure of thread-loops from the needle, advancement of the same for engagement and detention by the loop-detaining spur at one 100 side of the needle-path and retraction of the portions of the thread-loops held by the 105 loop-taker to the opposite side of the needle-path.

2. In a sewing machine, the combination 110 with a reciprocating needle, work-sustaining means, and means for producing between them relative lateral jogging movements, of a loop-taker for seizing thread-loops from the needle and presenting them for subsequent passage of the needle, a loop-detaining spur disposed intermediate the work-sustaining means and the loop-taker, and means for imparting to the loop-taker continuous rotary movements and bodily lateral reciprocatory movements crosswise of the needle-path whereby thread-loops are seized from the needle, advanced for engagement and detention by the loop-detaining spur at one side of the needle-path and distended upon the opposite side of the needle-path for passage of the needle. 115 120 125

3. In a sewing machine, the combination 130 with a reciprocating needle, work-sustaining means, and means for producing between them relative lateral jogging movements, of a loop-taker for seizing thread-

- loops from the needle and spreading them for subsequent passage of the needle, loop-taker actuating means, means for imparting to the loop-taker lateral jogging movements 5 in substantially the direction of said relative jogging movements, and a loop-detainer for holding deflected from their normal lead to the work the thread-loops spread by the loop-taker.
- 10 4. In a sewing machine, the combination with a reciprocating needle, work-sustaining means, and means for producing between them relative lateral jogging movements, of a loop-taker for seizing thread-loops from the needle and spreading them for subsequent passage of the needle, actuating means for imparting to the loop-taker loop-seizing movements in substantially the direction of said relative jogging 15 movements, means for imparting to the loop-taker lateral jogging movements in the direction of and beyond the normal range of its loop-seizing movements, and a loop-detainer adapted to engage the thread-loops 20 intermediate the loop-taker and the work-sustaining means.
- 15 5. In a sewing machine, the combination with a reciprocating needle, work-sustaining means, and means for producing between them relative lateral jogging movements, of a loop-taker for seizing thread-loops from the needle and presenting them for subsequent passage of the needle, a loop-detaining spur disposed intermediate the 25 work-sustaining means and the loop-taker, means for imparting to the loop-taker operative loop-seizing movements, and means for imparting to the loop-taker lateral jogging movements of greater frequency than the said relative jogging movements whereby thread-loops seized by the loop-taker are carried into engagement with and held by said spur upon one side of the needle-path and are distended by the looper upon the 30 opposite side of the needle-path.
- 20 6. In a sewing machine, the combination with a reciprocating needle, work-sustaining means, and means for producing between them relative lateral jogging movements, of a loop-taker adapted to perform its loop-seizing movements in the direction of said lateral jogging movements, a shaft upon which said loop-taker is mounted, means for turning said shaft and through it imparting 35 loop-seizing movements to the loop-taker, and means for imparting to said shaft lateral jogging movements in the same direction as said relative jogging movements.
- 25 7. In a sewing machine, the combination with a reciprocating needle, work-sustaining means, and means for producing between them relative lateral jogging movements, of a loop-taker adapted to perform its loop-seizing movements in the direction of said 40 lateral jogging movements, a shaft upon

which said loop-taker is mounted, a laterally movable slide-block in which said shaft is journaled adjacent the loop-taker, and means applied to said shaft independently of the slide-block for imparting to it and to 70 said slide-block lateral jogging movements.

8. In a sewing machine, the combination with a reciprocating needle, work-sustaining means, and means for producing between them relative lateral jogging movements, of a loop-taker adapted to perform its loop-seizing movements in the direction of said lateral jogging movements, a shaft upon which said loop-taker is mounted, a laterally movable slide-block in which said 75 shaft is journaled adjacent the loop-taker, a swiveled bearing for said shaft remote from said slide-block, driving means applied to said shaft adjacent its swiveled bearing, and means applied to said shaft 80 adjacent the slide-block for imparting to it and to said slide-block lateral jogging movements.

9. In a sewing machine, the combination with a reciprocating needle, work-sustaining means, and means for producing between them relative lateral jogging movements, of a loop-taker adapted to perform its loop-seizing movements in the direction of said lateral jogging movements, a shaft 85 upon which said loop-taker is mounted, actuating means for said shaft, a laterally movable support for said shaft, an eccentric upon said shaft, a fixed stud, and a connecting rod having a strap embracing said eccentric and a connection with said stud.

10. In a sewing machine, the combination with a reciprocating needle, work-sustaining means, and means for producing between them relative lateral jogging movements, of a loop-taker adapted to perform its loop-seizing movements in the direction of said lateral jogging movements, a needle-guard movable into and out of operative relation with the needle, a common laterally movable 105 support for said loop-taker and needle-guard, means for imparting lateral jogging movements to said support, and means for imparting differential operative movements to said loop-taker and needle-guard.

11. In a sewing machine, the combination with a reciprocating needle, work-sustaining means, and means for producing between them relative lateral jogging movements, of a loop-taker adapted to perform its loop-seizing movements in the direction of said lateral jogging movements, a needle-guard movable into and out of operative relation with the needle, a common laterally movable support for said loop-taker and needle-guard, means for imparting lateral jogging movements to said support, means for imparting rotary movements to the loop-taker, and means connected with the needle-guard 115 for moving it into operative relation with 120 125 130

the needle preparatory to the loop-seizing action and for retracting it at a greater speed than that at which the loop-taker moves in seizing and distending needle-thread loops.

12. In a sewing machine, the combination with a reciprocating needle, work-sustaining means, and means for producing between them relative lateral jogging movements, of a loop-taker adapted to perform its loop-seizing movements in the direction of said lateral jogging movements, a needle-guard movable into and out of operative relation with the needle, a common laterally movable support for said loop-taker and needle-guard, means for imparting lateral jogging movements to said support, means for imparting rotary movements to the loop-taker, and means connected with the needle-guard for moving it into operative relation with the needle preparatory to the loop-seizing action and for retracting it at a greater speed than that at which the loop-taker moves in seizing and distending needle-thread loops and for positively locking the needle-guard retracted from the range of movement of the loop-taker.
13. In a sewing machine, the combination with a reciprocating needle, work-sustaining means, and means for producing between them relative lateral jogging movements, of a loop-taker adapted to perform its loop-seizing movements in the direction of said lateral jogging movements, a needle-guard, a shaft upon which said loop-taker is mounted, a shaft upon which the needle-guard is mounted, a common laterally movable support for said shafts, means for imparting lateral jogging movements to said shafts, an actuating cam on the loop-taker shaft, and a follower for said cam on the needle-guard shaft.
14. In a sewing machine, the combination

with a reciprocating needle, work-sustaining means, and means for producing between them relative lateral jogging movements, of a loop-taker adapted to perform its loop-seizing movements in the direction of said lateral jogging movements, a needle-guard, a shaft upon which said loop-taker is mounted, a shaft upon which the needle-guard is mounted, a common laterally movable support for said shafts, means for imparting lateral jogging movements to said shafts, an actuating cam fixed upon the loop-taker shaft and formed peripherally upon opposite sides respectively with a concentric and an eccentric portion, and a cam-follower fixed upon the needle-guard shaft and provided with divergent arms adapted to closely embrace the concentric portion of said cam and provided with means whereby one of said arms is adapted to follow the contour of the eccentric portion of said cam.

15. In a sewing machine, the combination with a reciprocating needle, work-sustaining means, and means for producing between them relative lateral jogging movements, of a loop-taker adapted to perform its loop-seizing movements in the direction of said lateral jogging movements, a shaft upon which said loop-taker is mounted, actuating means for said shaft from which said loop-taker derives its loop-seizing movements, and means acting through said shaft and independently of its actuating means for imparting to the loop-taker an additional movement in loop-seizing direction.

In testimony whereof, I have signed my name to this specification, in the presence of two subscribing witnesses.

ALBERT F. FIFIELD.
